UNITED STATES PATENT OFFICE.

PEDRO FILIPPINI, OF MAZATLAN, MEXICO.

FAN ATTACHMENT FOR SEWING-MACHINES.

1,366,776.

Specification of Letters Patent. Patented Jan. 25, 1921.

Application filed October 14, 1919. Serial No. 330,656.

To all whom it may concern:

Be it known that I, PEDRO FILIPPINI, a subject of the King of Italy, residing at Mazatlan, State of Sinaloa, Mexico, have 5 invented certain new and useful Improvements in Fan Attachments for Sewing-Machines, of which the following is a specification.

This invention relates to fan attachments 10 for sewing machines and has as its object to provide an attachment which may be readily applied to and detached from practically any standard make of sewing machine and which will, in the operation of 15 the machine, create a cooling current of air which will be blown in the direction of the operator of the machine to afford comfort while working.

Another object of the invention is to provide 20 an attachment of the class mentioned so constructed that the same may be applied without the use of tools of any description and when in place upon the fly wheel of the machine will be securely held in position and therefore not liable to work loose 25 or be thrown off from the wheel.

A further object of the invention is to so construct the device that while fan blades of maximum size and considerable pitch 30 may be employed without interfering in any way with the belt or other parts of the sewing machine to which the device is applied, the blades are furthermore so proportioned and of such contour as to most effectually 35 direct the air currents in the operator's direction.

In the accompanying drawings:

Figure 1 is a view in elevation of the device applied to a sewing machine of a standard type;

Fig. 2 is a side elevation of the device;

Fig. 3 is a vertical longitudinal sectional view through the hub portion thereof.

I have designed the attachment embodying 45 the present invention with the object in view of rendering the same practically universal in its application and as a general rule it will be found that the structure illustrated in the drawings and hereinafter described is adaptable to various standard makes of machines. It will be understood, however, that, within the terms of the claim, modifications may be resorted to either in the proportions or shapes of the parts whenever 55 found necessary.

In the drawings the numeral 1 indicates

in general the head of a sewing machine, 2 the fly wheel thereof, and 3 the usual milled nut which is fitted onto the shaft of the fly wheel, the milled flange of this nut being 60 indicated by the numeral 4. These parts or elements are of the usual construction and are only herein referred to in order to illustrate the application of the invention.

The attachment comprises a hub which is 65 indicated in general by the numeral 5, the said hub comprising a hollow cylindrical body 6 of sheet metal or other material suitable for the purpose. At one end this body is formed with an inwardly directed peripheral flange 7 which is designed to bear against the end face of the nut 3 as shown in Fig. 1 of the drawings. The opposite end of the body is closed by a head indicated by the numeral 8 which head may also be of 75 sheet metal and is formed with a flange 9 crimped over a flange 10 formed at the last mentioned end of the said body 6, the parts being thus permanently united. The blades of the fan attachment are indicated in general by the numeral 11 and each blade has a shank 12 which is disposed against the outer face of the head 8 and riveted or otherwise secured as indicated by the numeral 13, to the said head. The blades 11 all face 85 in the direction of rotation of the attachment and the advancing side or edge portion of each blade, indicated by the numeral 14, occupies nearly the plane of the head 8 of the hub of the attachment, each blade being curved from this edge in a rearward and lateral direction so as to provide a deflected side 15 which is presented obliquely in the direction of rotation of the attachment. At this point it will be evident that 95 the advancing edges of the blades will cleave the air and the following edge portions of the blades, being laterally deflected, will force the air in the general direction of the front of the machine head and consequently 100 laterally toward the operator of the machine.

In order that the hub 5 may be attached to the fly wheel of the machine so as to rotate with the said wheel, the said hub is 105 provided with a number of clip fingers indicated in general by the numeral 16. Each of these fingers comprises a leaf spring shank 17 the inner end of which is disposed to abut as at 18 against the overturned flange 9 of 110 the head 8 of the hub, a rivet or other suitable fastening element 19 being secured

through the said shank near its said end and through the wall of the hub. In this manner, while but a single rivet or other fastening element is employed, the shank will be 5 securely held in place and prevented from pivoting or twisting upon its pivot by reason of the fact that its said end bears squarely against the said flange 9. From its point of attachment, the shank is curved 10 slightly outwardly from the surface of the body 6 of the hub as most clearly shown in Fig. 3 of the drawings and is thence curved inwardly near its outer end, as at 20 in the direction of the axis of the hub. Each finger 15 is provided at the outer end of its shank with a shoulder 21 having an abrupt face 22 and an inclined face 23, the terminal of the shoulder being curved outwardly as at 24 to provide a lip by means of which the 20 clip finger may be sprung outwardly in detaching the device from the fly wheel of the machine. In applying the device, the same is disposed parallel to the fly wheel with the 25 faces 23 of the shoulder portions 21 engaging against the flange 4 of the nut 3 and the attachment is then bodily moved laterally in the direction of the fly wheel until the shoulders 21 ride over the said flange 4 and their faces 23 engage behind the said 30 flange as shown in Fig. 1. In this position of the parts, the flange 7 will bear, as previously stated, against the end face of the

nut, and the attachment will therefore be firmly clamped to the said nut for rotation with the same and the fly wheel, and will be 35 securely held against disengagement or being thrown off from the wheel. At the same time the attachment may be readily detached from the machine by outwardly springing the clip fingers as previously 40 stated.

Inasmuch as the hub 6 is hollow, it will be understood that should the nut 3 be provided with any projecting portions upon its end face, these portions will be accommodated within the hub 6 and will therefore not interfere with the attachment of the hub to the nut.

Having thus described the invention, what is claimed as new is:

An attachment of the class described comprising a hollow cylindrical hub having an inwardly projecting flange at one end constituting an abutment, and resilient clip fingers disposed against the outer side of the 55 hub and extending longitudinally thereof and secured at one end to the hub, the other end of each clip finger projecting beyond the said flanged end of the hub, and provided with a locking shoulder facing and 60 spaced from the said flange.

In testimony whereof I affix my signature.

PEDRO FILIPPINI. [L.S.]
